UNITED STATES PATENT OFFICE.

CLEARMONT V. BEST, OF CANTON, OHIO, ASSIGNOR OF TWO-THIRDS TO
JAY G. BEST AND LEWIS M. BACHTEL, OF SAME PLACE.

DESIGN FOR A VAPOR-BURNER FRAME.

SPECIFICATION forming part of Design No. 31,407, dated August 15, 1899.

Application filed July 18, 1899. Serial No. 724,326. Term of patent 14 years.

To all whom it may concern:

Be it known that I, CLEARMONT V. BEST, a citizen of the United States, residing at Canton, in the county of Stark and State of Ohio, have invented and produced a new and original Design for a Vapor-Burner Frame, of which the following is a specification, reference being had to the accompanying drawings, forming part thereof.

10 Figure 1 is a side view. Fig. 2 is an edge view. Fig. 3 is a top view.

As shown in the drawings, the leading or material feature of my design consists in the cylindrical portion or part 1, having at its 15 upper portion a series of grooves 2 and holes 2^a, formed through the cylindrical portion 1 in the grooves 2, and below the groove portion of the cylinder one collar or flange 3, said collar or flange consisting of the beveled portion 4, below which beveled portion is located

20 the straight body or shank 5, the bottom or lower portion of which is provided with the narrow web 6, below which web or narrow portion is located the flange 7, and below the flange 7 is located the straight vertical portion 8, said lower vertical portion 8 being joined 25 with the horizontal part or portion 9, and

above said horizontal portion 9 extends the side flange 10, at the upper end of which is located the laterally-extended cylindrical portion 11, and above said cylindrical portion 11 is located the flange 12, which flange extends from the cylindrical portion 11 to the bottom or under side of the beveled portion of the collar.

30 The upper end or portion of the cylindrical portion 1 is provided with the inward-protecting flange 13 and the lower portion or part 8 provided with the cone-disk 14, all of which parts are arranged substantially as shown in 35 the drawings.

Having fully described my invention, what I claim as new, and desire to secure by Letters Patent, is—

40 The design for a vapor-burner frame as 45 herein shown and described.

In testimony that I claim the above I have hereunto subscribed my name in the presence of two witnesses.

CLEARMONT V. BEST.
